LIQUID DISPENSING DEVICE

Everett J. Weatherbie, Salinas, Calif.

Application September 4, 1951, Serial No. 245,000

1 Claim. (Cl. 222—263)

This invention is directed to, and it is the major object to provide, a novel device for dispensing a liquid in bulk from a supply container; the invention being especially designed—but not limited—for use to dispense lubricating oil in automotive service stations or the like.

Another important object of the invention is to provide a liquid dispensing device which eliminates the need of hand pumping from the supply container; the liquid being force-fed to a spigot by compressed air, and there being means to automatically maintain the device under pressure.

A further object of the invention is to provide a liquid dispensing device which is wholly self-contained or unitary, including the mechanism to produce the compressed air; the device thus being capable of ready and convenient installation on any supply container having a top opening through which the device depends.

A still further object of the invention is to provide a liquid dispensing device which continuously maintains a quantity of the liquid under pressure and therefore ready for immediate dispensing; the initial dispensing of the liquid thus not being dependent on the operation of the machine and so does not have to await starting of the mechanism which produces such pressure.

An additional object of the invention is to provide a liquid dispensing device which is simple and compact in structure; being designed for ease and economy of manufacture and maintenance.

Still another object of the invention is to provide a practical and reliable liquid dispensing device, and one which will be exceedingly effective for the purpose for which it is designed.

These objects are accomplished by means of such structure and relative arrangement of parts as will fully appear by a perusal of the following specification and claim.

In the drawings:

Fig. 1 is a side elevation of the device as in use.

Fig. 2 is an enlarged sectional elevation of the same.

Fig. 3 is an enlarged fragmentary sectional elevation of the lower end portion of the device; the view being on line 3—3 of Fig. 2.

Referring now more particularly to the characters of reference on the drawings, the device is herein described as used for dispensing oil, and such device comprises a vertically elongated reservoir, indicated generally at 1.

The reservoir 1 and all of the attached parts, as hereinafter described, is a readily manually portable structure; such reservoir including an upper cylinder 2 and a lower cylinder 3 in communication. The lower cylinder 3 is of substantially lesser diameter than the upper cylinder 2 and provides, in effect, an elongated depending neck adapted to depend into a bulk supply tank or container 4 for the liquid.

The lower cylinder 3 depends into the bulk supply tank 4 through a top opening therein, which is defined by an annular rim 5; there being a supporting collar 6 on the upper end of the lower cylinder 3 which rests on said

2

rim 5, being located in the latter by a depending peripheral flange 6a integral with said collar.

The lower cylinder 3 is of a length such that it terminates at its lower end in adjacent but spaced relation to the bottom 7 of the bulk supply tank 4.

The lower cylinder 3 is closed at its lower end by a bottom cap 8, and a gear type pump 9 is disposed below the bottom cap 8 in alignment, being suspended in fixed relation from said cap by circumferentially spaced bracket arms 10.

The pump 9 includes an intake port 11 and a discharge port 12; the former being in communication with the bulk supply tank 4 close to the bottom 7, while the discharge port 12 is in communication with a feed pipe 13 which leads upwardly through the bottom cap 8. Immediately above the bottom cap 8 the feed pipe 13 is fitted with a ball check valve 14 which opens into the lower cylinder 3; i. e. closes toward the pump.

The pump drive shaft 15 projects upwardly into the space between the pump 9 and bottom cap 8, there being coupled—as at 16—to the lower end of a vertical drive shaft 17 which extends full length through the reservoir 1. Above the upper cylinder 2 the vertical drive shaft 17 is coupled, as at 18, to the downwardly projecting shaft 19 of an electric drive motor 20; the motor 20 being supported from the top 21 of the upper cylinder 2 by pedestal arms 22.

Throughout the length of the reservoir 1 the vertical drive shaft 17 runs in protected relation in a conduit or tubular housing 23 sealed off with respect to the interior of the upper cylinder 2 and lower cylinder 3.

An outlet pipe 24 extends within the reservoir 1 from a point adjacent the bottom cap 8 upwardly in said reservoir; thence turning and passing out of the upper cylinder 2 near the top thereof. From this point the outlet pipe 24 projects a short distance forwardly and is fitted, on its free end, with a normally closed spigot 25 adapted to discharge into a dispensing can 26 normally disposed therebelow.

Operation

In use, the above described oil dispensing device is supported on the bulk supply tank 4 in the manner described, and the electric motor is connected to a source of electricity.

With energization of the motor 20 it drives the pump 9 through the medium of the drive shaft 17, whence oil is drawn into the pump through the intake port 11 from the bulk supply tank 4, and is delivered through the feed pipe 13 and check valve 14 into the reservoir 1.

After the pumped oil is introduced in a certain quantity into the reservoir 1 air pressure builds up in the upper cylinder 2, providing an air dome. An automatic or pressure-responsive switch 27 is mounted atop the upper cylinder 2 in communication therewith, and is wired into the circuit for the motor 20 in a manner to shut off such motor 20 when the pressure reaches a predetermined maximum amount and to turn on the motor when the pressure lowers to a predetermined minimum.

With the foregoing switching arrangement the reservoir 1 is always maintained with a substantial quantity of oil therein under the pressure of an air dome; the pressure-responsive switch 27 being adjustable in its limits whereby it may be set so that the device will work effectively with oils of different viscosities, etc.

When it is desired to withdraw oil, the spigot 25 is turned on and immediately oil feeds through the outlet pipe 24 from the reservoir 1 under the pressure of the air dome. This is a substantial advantage, for the reason that the operator does not have to wait for starting of the motor 20 or building up of pumping pressure before delivery is obtained from the spigot 25. However, the

motor 20 will run at the proper time to maintain the air dome at sufficient pressure for proper oil delivery from the device.

As the pressure creating mechanism is included in the device, no external source of air pressure is required, and consequently the device is adaptable for use at any point and in connection with any bulk supply tank having a top opening; a source of electricity being the only requirement.

By reason of its compact unitary structure the device is readily mounted on, or removed from, a bulk supply tank, and when in position thereon does not occupy floor space beyond that required for such bulk supply tank.

With the described device, oil may be dispensed in a quick, effective manner and without attention on the part of the operator other than the manual opening of the spigot 25.

From the foregoing description it will be readily seen that there has been produced such a device as substantially fulfills the objects of the invention, as set forth herein.

While this specification sets forth in detail the present and preferred construction of the device, still in practice such deviations from such detail may be resorted to as do not form a departure from the spirit of the invention, as defined by the appended claim.

Having thus described the invention, the following is claimed as new and useful, and upon which Letters Patent are desired:

A device to dispense liquid from a bulk supply tank having a top opening, the device comprising a pressure-tight reservoir adapted to depend into the tank through the opening, means to removably support the reservoir from the tank with the upper portion of the reservoir

above the tank, a dispensing conduit leading upwardly in the reservoir from adjacent the lower end to the exterior thereof above the tank, a vertical-axis motor mounted on top of the reservoir, a vertical-axis gear pump disposed adjacent and below the reservoir with its intake open to the liquid in the tank and arranged to be removed as a unit with the reservoir from within the tank, means supporting the pump from the bottom of the reservoir in clearance relation thereto and so that the drive shaft of the pump is in vertical alinement with the drive shaft of the motor, a pipe leading from the discharge of the pump into the reservoir through the bottom thereof in sealed relation therewith, a shaft unit connecting the motor and pump shafts and extending through the reservoir, and a tubular housing about the shaft unit within the reservoir and connected to the top and bottom walls of the reservoir in pressuretight relation; the shaft unit including a coupling member connecting said unit with the pump shaft and disposed in the space between the reservoir and pump.
